(57) **CLAIM**

The ornamental design for a bottle, as shown and described.

DESCRIPTION

FIG. 1 is an isometric view of a top, front, and right side of a bottle;

FIG. 2 is a right side elevational view of the bottle of FIG. 1;

FIG. 3 is a left side elevational view of the bottle of FIG. 1; FIG. 4 is a front elevational view of the bottle of FIG. 1; FIG. 5 is a rear elevational view of the bottle of FIG. 1; and, FIG. 6 is a top plan view of the bottle of FIG. 1.

The dash-dash-dash lines are included for the purpose of illustrating portions of the bottle that form no part of the claimed design. The dash-dot-dash lines are included for the purpose of illustrating boundary lines and form no part of the claimed design.
